HANDLE FOR KITCHEN UTENSIL

Fred S. Steiner, Woodmere, N.Y., assignor to Bonny Products, Inc., Lynbrook, N.Y., a corporation of New York

Filed Apr. 28, 1969, Ser. No. 16,922

Term of patent 14 years

Int. Cl. D8—02

U.S. Cl. D44—29

FIG. 1 is a perspective view of a handle for a kitchen utensil showing my new design;

FIG. 2 is a right side elevational view;

FIG. 3 is a top plan view;

FIG. 4 is a bottom plan view; and

FIG. 5 is a rear elevational view.

I claim:

The ornamental design for a handle for kitchen utensil, as shown.
